ELECTRONIC AMPLIFIER AND MODIFIER

Robert G. Rowe, Niagara Falls, N. Y.

Application October 15, 1943, Serial No. 506,381

8 Claims. (Cl. 250—27)

1

My invention relates, generally, to an electronic amplifier and modifier for controlling and modifying the effective grid voltage-anode current characteristics in electron tube circuits and, more specifically, to an improved circuit for sensitive control devices.

The design of amplifying, modulating, signalling, counting, cycling and like apparatus which depends for its function on variations in electronic tube anode-cathode voltage and current is well known in the electronic art.

In vacuum tube amplification, variations in anode current through a serially connected resistor develop a varying potential for application to the grid of the ensuing tube. In modulation, variations in the radio frequency amplifier plate voltage produce similar variations in the carrier power output. In photoelectric, inductive, capacitive and like apparatus, variations in associated vacuum tube anode currents operate serially coupled resistors, relays and other current responsive devices.

In all of these and many other systems it is the variation in current or the variation in voltage, the maximum to minimum ratio, which in a large part determines the effectiveness of the control. In conventional amplifiers the variation in voltage or the voltage swing on the grid of the tube is a determining factor in the output voltage of the stage. In conventional modulators the variation in anode-cathode radio frequency amplifier voltage largely determines the percentage modulation. In photoelectric, inductive and capacitive apparatus the amount of variation in anode current largely determines the reliability, ruggedness and efficiency of the entire device.

I have found, however, that for many applications the variation in voltage or current, the maximum to minimum ratio, is insufficient to properly actuate the coupled device. Particularly in photoelectric, inductive and capacitive equipment fragile, expensive, sensitive relays must be used to respond to the small current changes produced. Further, these sensitive relays usually are not designed to handle high secondary voltages and currents. Often, they are used in the control circuits of larger relays with high secondary power handling capabilities adding to the expense and complexity of the apparatus. Still further, sensitive relays are more susceptible to damage and faulty operation due to low contact pressure and other effects.

It is, accordingly, an object of my invention to amplify these variations in current and voltage to increase the maximum to minimum ratio.

2

Still another object of my invention is to further control or modify these variations, the ratio, rate and slope of maximum to minimum, to effect new and useful circuit characteristics.

5 The aforementioned objects and other objects ancillary thereto I prefer to accomplish, in short, by inserting serially in the master circuit a controllable resistance device with at least an anode, control grid and cathode together with a means for biasing the control grid of the resistive element which is responsive to current or voltage variation in the master circuit.

10 Other and further objects of my invention reside in the method and apparatus employed therein as set forth more fully in the specification hereinafter following by reference to the accompanying drawing, in which

15 The single figure schematically illustrates a capacity sensitive circuit arrangement embodying 20 one of the principles of my invention.

With reference to the drawing, in which cathode heaters are eliminated for convenience in drawing, master tube 1 is employed in a modified Hartley oscillator circuit, with variable condenser 2 and inductance 3 comprising the resonant tank circuit. Plate blocking condenser 4 offers a low impedance to radio frequency current, but effectively isolates the direct current component on plate 5 of vacuum tube 1 from the grounded tank coil assembly. Radio frequency choke 6 offers a low resistance to the flow of direct current but a high impedance to the alternating current component appearing on plate 5 of vacuum tube 1. By-pass condenser 7 effectively shunts to ground 30 stray radio frequency currents which are not impeded by choke 6. Grid condenser 8 offers a low impedance to regenerative radio frequency current inductively obtained from tank coil 3 to provide excitation for grid 9 of tube 1, but effectively isolates grid 9 from ground. I have found that 35 shunting grid condenser 8 by a resistor as usually employed in the Hartley circuit partially impairs sensitivity of this particular arrangement and that, especially when condenser 8 exhibits appreciable leakage conductance, additional resistance may be omitted. The resistance from grid 9 to the cathode of tube 1 is somewhat critical in securing optimum circuit sensitivity and the proper value is best determined by experiment.

40 Such an oscillator circuit, which is connected as shown in the drawing to leads A and B, is in effect a variable resistance device across leads A and B, the resistance of which varies in accordance with the condition of resonance or anti-

55

resonance in the link-coupled external tank circuit described below.

Pickup coils 10 and 11 provide link coupling to the capacity-sensitive external tank circuit comprising coil 12, condenser 13, antenna 14 and ground.

Normally closed relay 15 controls the signalling, counting, cycling or like circuit to be operated by capacity variations in the external tank circuit. When the generator circuit comprising tube 1 and its associated components is oscillating, by proper selection of components the external tank circuit comprising coil 12, condenser 13, antenna 14 and ground can be tuned to resonance with the oscillator. Components can be so adjusted that when the external tank circuit is tuned to resonance with the oscillator, tube 1 will draw maximum anode current, and when this condition of resonance is disturbed by added capacity between antenna 14 and ground tube 1 will draw less than maximum anode current.

Thus, in a condition of resonance, current responsive relay 15 will hold open contacts 16 and 17 which control the external signalling, counting, cycling or like circuit. When resonance is disturbed by a capacitance variation in the link coupled external tank circuit, the armature of current responsive relay 15 will drop out and close contacts 16 and 17. This circuit is well known in the electronic art.

However, I have found that the anode current change through current responsive relay 15 from a condition of resonance to off-resonance as occasioned by the capacity changes which I encounter is insufficient to properly operate the relay which I desire to employ.

One phase of my invention resides in the hereinafter described improvements; wherein a resistive device, vacuum tube 18, comprising at least an anode 19, control grid 20 and cathode 21 is inserted serially in the master circuit, that is to say, in series with battery C, relay 15, resistor 25 and oscillator supply leads A and B; and wherein bias potential on control grid 20 is supplied by the IR drop through resistor 22 as determined by the anode current of anode 23 of vacuum tube 24; and wherein the anode current of vacuum tube 24 is responsive to current changes in the master circuit through resistor 25, grid 26 and cathode 27.

In a condition of resonance between the oscillator and the link coupled external circuit the anode current of tube 1 is maximum. Thus, the bias voltage on grid 26 of tube 24 is maximum as determined by the IR drop across resistor 25. Because of high negative bias on grid 26 of tube 24, anode 23 draws little current through resistor 22 and minimum bias appears on the grid 20 of tube 18. With low grid bias, the resistance of tube 18 is low, a maximum voltage appears on the oscillator as measured from cathode 27 of vacuum tube 24 to cathode 21 of vacuum tube 18, and a maximum current flows through the field coil of current responsive relay 15.

In a condition of off-resonance between the oscillator and the link coupled external circuit as occasioned by the capacitive changes which I encounter, the anode current of tube 1 drops to a lower than maximum value. Thus, the bias voltage on grid 26 of tube 24 decreases as determined by the IR drop across resistor 25. Because of the lower negative bias on grid 26 of tube 24, anode 23 begins to draw more current through resistor 22 and more negative bias appears on grid 20 of tube 18. With increasing negative grid

bias, the resistance of tube 18 becomes higher, and a lower than maximum voltage appears on the oscillator as measured from cathode 27 of vacuum tube 24 to cathode 21 of vacuum tube 18. As the voltage becomes progressively lower on the oscillator, vacuum tube 1, the current through resistor 25 and, ipso facto, the negative bias on grid 26 of tube 24 becomes progressively smaller. Anode 23 of vacuum tube 24 draws progressively more current through resistor 22, and more negative bias appears on grid 20 of tube 18. The resistance of tube 18 progressively increases and current flowing in the master circuit through the field coil of relay 15 progressively decreases to an equalization point.

I have found that the use of this controllable resistive element increases the maximum to minimum current ratio through the serially inserted control relay. I am able to employ less expensive, more reliable current responsive relays, secure greater sensitivity of the capacitive element and insure sharper and more reliable relay action. Obviously, relay 15 may be inserted serially between the cathode of tube 1 and resistor 25, above or below the junction of cathode 27; or between radio frequency choke 6 and cathode 21 of tube 18, to further increase sensitivity by eliminating the reactive plate current component of tube 24.

Otherwise, my invention has broad application in the radio and electronic art. In the case of conventional electronic tube amplifiers, the IR voltage drop developed across a resistor inserted serially in the anode-cathode circuit is impressed on the grid of the ensuing tube. When these tubes are operated on the straight-line portion of the grid voltage-anode current curve, the amplification factor or μ of the tube remains substantially constant and the maximum to minimum voltage or current ratio throughout the system remains substantially uniform. Although the peak values of current or voltage are elevated, the minimum values are similarly elevated, in a manner such that the ratio between the two remains constant. By inserting my controlled resistive element serially in one or more of the amplifier stages, I have found that I can either increase or decrease the ratio between the maximum and minimum values of current or voltage by slight circuit modifications. Thus, it becomes feasible to augment the amplification factor of an amplifying stage, or modify it in a desirable manner. It is to be understood that I do not pretend to modify the inherent characteristics of a given vacuum tube, but only the effective characteristics of the circuit entity.

To reduce cross-modulation and modulation-distortion in radio receivers and to obtain other known effects, manufacturers are supplying so-called super-control or remote cut-off amplifier tubes of a modified grid structure designed to handle both large and small grid input signals with a minimum of distortion over a wide range. As noted on page 15 of the R. C. A. Receiving Tube Manual, Technical series RC-14, the grid of the super-control amplifier is wound with coarse spacing in the center and close spacing at each end. When weak signals and low grid bias are applied to the tube, the effect of the non-uniform turn spacing of the grid on tube characteristics is essentially the same as for uniform spacing. As the grid bias is made more negative to handle larger input signals, the electron flow from the sections of the cathode enclosed by the ends of the grid is cut off. The tube character-

istics are then dependent on the electron flow through the coarse section of the grid. As noted further, while the curves manifest by the super-control grid and the uniformly spaced grid are similar at small grid bias and high plate current ratings, the plate current of the super-control amplifier drops more slowly with large values of bias voltage.

I have found that I am able to secure this aforementioned super-control, remote cut-off and variable mu function using a tube with a uniformly spaced grid structure if I employ the principles of my invention and insert a variable resistance element serially in the master circuit and control its resistance from current flow in the master circuit.

To amplitude modulate a radio frequency amplifier, the amplifier voltage is increased and reduced by the conventional modulators at modulation frequencies. I have found that by inserting serially, in place of the secondary of a modulation transformer for example, the variable resistance element herein disclosed I am able to accomplish the same effect when I control the resistance of the resistive device at modulation frequencies. Further, by the incorporation of a current responsive control means such as I have illustrated in Figure 1, as tube 24 and its associated components, and by designing this means to keep the proper average plate voltage on the radio frequency amplifier, I can increase the sensitivity of this modulation means to the point where it is practical.

While I have described my invention in only several of its preferred embodiments I am aware that various alterations and modifications of the present invention may become apparent and immediately suggest themselves to those versed in the art to which this invention is directed. Thus, any and all such alterations and modifications are to be considered within the purview of the present invention except as limited by the hereinafter appended claims.

What I claim is:

1. A circuit arrangement for amplifying the current change in a series circuit, comprising in series a source of at least substantially constant voltage, a variable resistance control device, a current responsive device constituting a load, and the anode and cathode of an electron tube, further provided with at least one control grid electrode; resistance means connecting the grid and cathode of the last named electron tube, means to supply a potential difference between the last named electrodes, said means consisting of a second electron tube with at least an anode, cathode and control grid electrode, and means for connecting the anode of the second named tube to the grid of the first named tube and the grid and cathode of the second named tube across a resistance placed in the series circuit, whereby the maximum to minimum current ratio in the series circuit is increased.

2. A circuit arrangement for amplifying the current change in a series circuit, comprising in series a source of at least substantially constant voltage, an electron tube oscillator constituting with its output circuit a variable resistance control device, a current responsive device constituting a load, and the anode and cathode of an electron tube, further provided with at least one control grid electrode; resistance means connecting the grid and cathode of the last named electron tube, means to supply a potential difference between the last named electrodes, said means

consisting of a second electron tube with at least an anode, cathode and control grid electrode, and means for connecting the anode of the second named tube to the grid of the first named tube and the grid and cathode of the second named tube across a resistance placed in the series circuit, whereby the maximum to minimum current ratio in the series circuit is increased.

3. A circuit arrangement for amplifying the current change in a series circuit, comprising in series a source of at least substantially constant voltage, a variable resistance control device, a relay device constituting a load, and the anode and cathode of an electron tube, further provided with at least one control grid electrode; resistance means connecting the grid and cathode of the last named electron tube, means to supply a potential difference between the last named electrodes, said means consisting of a second electron tube with at least an anode, cathode and control grid electrode, and means for connecting the anode of the second named tube to the grid of the first named tube and the grid and cathode of the second named tube across a resistance placed in the series circuit, whereby the maximum to minimum current ratio in the series circuit is increased.

4. A circuit arrangement for amplifying the current change in a series circuit, comprising in series a source of at least substantially constant voltage, an electron tube oscillator constituting with its output circuit a variable resistance control device, a current responsive device constituting a load, and the anode and cathode of an electron tube, further provided with at least one control grid electrode; resistance means connecting the grid and cathode of the last named electron tube, means to supply a potential difference between the last named electrodes, said means consisting of a second electron tube with at least an anode, cathode and control grid electrode and means for connecting the anode of the second named tube to the grid of the first named tube and the grid and cathode of the second named tube across said load.

5. A circuit arrangement for amplifying the current change in a series circuit, comprising in series a source of at least substantially constant voltage, an electron tube oscillator constituting with its output circuit a variable resistance control device, a relay device constituting a load, and the anode and cathode of an electron tube, further provided with at least one control grid electrode; resistance means connecting the grid and cathode of the last named electron tube, means to supply a potential difference between the last named electrodes, said means consisting of a second electron tube with at least an anode, cathode and control grid electrode and means for connecting the anode of the second named tube to the grid of the first named tube and the grid and cathode of the second named tube across said relay device.

6. A circuit arrangement for amplifying the current change in a series circuit, comprising in series a source of at least substantially constant voltage, a current responsive load device, a negative impedance, and a variable impedance control device; said last named impedance including the anode-cathode circuit of an electron tube oscillator provided with a load-circuit adaptable to resonance or anti-resonance with said oscillator.

7. A circuit arrangement for amplifying the current change in a series circuit, comprising in

series a source of at least substantially constant voltage, a current responsive load device, a negative impedance, and a variable impedance control device; said last named impedance including the anode-cathode circuit of an electron tube oscillator, a remote load-circuit adaptable to resonance or anti-resonance with said oscillator and means to link-couple said load-circuit to said oscillator.

8. A circuit arrangement for amplifying the current change in a series circuit, comprising in

series a source of at least substantially constant voltage, a relay device, a negative impedance, and a variable impedance control device; said last named impedance including the anode-cathode circuit of an electron tube oscillator provided with a load-circuit adaptable to resonance or anti-resonance with said oscillator, whereby the anode circuit impedance of said oscillator is controlled by the tuning of said load-circuit.

ROBERT G. ROWE.
